Des. 210,733
Patented Apr. 9, 1968

210,733

CHRISTMAS ORNAMENT

Dario Moranduzzo, Via Aretina 161, Florence, Italy

Filed May 9, 1967, Ser. No. 7,027

Term of patent 7 years

(Cl. D29—1)

FIG. 1

I claim:

The ornamental design for a Christmas ornament, as shown and described.
